UNITED STATES PATENT OFFICE.

WILLIAM J. WATTERS, OF CHICAGO, ILLINOIS.

BINDER-FRAME.

No. 796,546.

Specification of Letters Patent.

Patented Aug. 8, 1905.

Application filed September 17, 1903. Serial No. 173,509.

To all whom it may concern:

Be it known that I, WILLIAM J. WATTERS, a citizen of the United States, residing at Chicago, in the county of Cook and State of Illinois, have invented certain new and useful Improvements in Binder-Frames, of which the following is a specification.

This invention relates to loose-leaf binder-frames; and its object is to provide a strong and substantial frame adapted to be easily and quickly adjusted without buckling or getting out of order otherwise under the strains to which it is subjected and which can be made inexpensively of comparatively few parts.

In the drawings I have illustrated several embodiments of the invention, and referring thereto, Figure 1 is a plan view. Fig. 2 is a similar view showing a different construction. Fig. 3 is also a plan view showing a construction in which the travelers are at the ends of the screw-rod when the frame is closed. Fig. 4 is a sectional view on the line 4 4 of Fig. 3. Fig. 5 is a sectional view on the line 5 5 of Fig. 3. Fig. 6 shows a right-threaded screw for operating two travelers. Fig. 7 is a detail view.

In the drawings like numerals of reference designate corresponding parts in the several figures, and referring thereto, 10 is a back member and 11 represents relatively movable members, to which the covers (not shown) are attached. These members are provided with interfitting ends of suitable construction, the drawings showing the ends 12 on the movable members arranged to work within and close to the ends 13 on the back member, and thus constructed these ends act as guides for the movable members and assist in maintaining the members in proper relative position. The movable members are adjusted relatively by a screw-rod 14, which is suitably mounted in bearings 15 on the back member and shaped at one end 16 to receive an operating-key. (Not shown.) This rod carries one or more threaded travelers 17, which project on either side thereof and are operatively connected to the movable members to move said members relatively as the traveler is moved on and by the screw-rod longitudinally of the frame. The traveler carries pins or rollers 18, which are arranged to work in oppositely-directed guides on the movable members. These guides cross each other and are preferably in the form of grooves or slots 19 in triangular plates 20, attached to and forming part of the movable members. It will be readily un-

derstood that as the traveler moves on the screw-rod its guide-pins or rollers working in slots 19 will operate to move the movable members relatively, and thus extend or contract the frame, as desired.

My invention may be embodied in different specific forms, some of which I have shown in the drawings.

In Fig. 1 two travelers are mounted on a right and left threaded screw-rod 14 and operatively connected with the movable members by engaging slots in two sets of overlapping triangular guide-plates 20, which have their apices 21 inwardly directed.

In Figs. 3 and 6 the constructions are substantially the same as in Fig. 1, except that in Fig. 3 the guide-plates are arranged with their apices outwardly directed, and in Fig. 6 the guide-plates are arranged with their apices pointing in the same direction and with the screw-rod right-threaded only. I may bend over the base 22 of one guide-plate to form a channel-guide groove to receive the base of the other guide-plate to maintain the members in proper relative position. Strips 23 may be fastened to the back member and arranged to engage the movable members, as shown in Figs. 2 and 3, if desired, to further assist in maintaining the relative position of the members.

In Fig. 2 a single traveler and set of cross guide-plates therefor are shown located at one end of the frame, and at the other end toggle-arms 24 are connected to the movable members and to a sleeve 25, movably mounted on the screw-rod and having connections 26 with the traveler. In this construction the movable plates are moved relatively by travelers working in the guide-slots, as heretofore described, and the toggle is simply employed to insure the even and regular movement of the movable members at each end thereof.

My improved binder-frame is strong and durable in construction, composed of few parts, and is comparatively inexpensive to manufacture. It can be adjusted easily and quickly to permit of the insertion or removal of leaves and can be clamped tightly upon the leaves to secure them rigidly in place. It will also be observed that the invention does not include any parts of comparatively delicate construction, and hence the frame can be easily manufactured and put together and is particularly strong and durable in construction.

The leaves will be arranged on telescopic posts 27 in the usual manner, these posts being indicated in broken lines only in Figs. 1 and 2 to avoid confusion. I may guide one of the plates 20 upon the other in the manner shown in Fig. 7, in which one plate is provided with a slot 28 to receive an antifriction-roller 29 on the other plate.

Without limiting myself to the exact construction and arrangement of parts herein shown and described, what I claim, and desire to secure by Letters Patent, is—

1. A binder-frame comprising two movable members, two guides carried by said members and crossing each other, and means for moving said guides relatively to move said members away from or toward each other.

2. A binder-frame comprising two movable members, guides carried by said members and crossing each other, and means for changing the point of crossing of said guides to move said members away from or toward each other.

3. A binder-frame comprising two movable members, guides carried by said members and crossing each other, a traveler movable on said guides, and means for moving the traveler to change the point of crossing of said guides and move said members away from or toward each other.

4. A binder-frame comprising a back member and two relatively movable members, guides carried by said movable members and crossing each other, a traveler movable on said guides, and a screw-rod mounted on said back member adapted to operate said traveler to change the point of crossing of said guides and move said movable members away from or toward each other.

5. A binder-frame comprising two relatively movable members, guides crossing each other and carried by said members, a traveler movable on said guides, and means for moving said traveler at a right angle with the line of movement of said movable members.

6. A binder-frame comprising a back member and two relatively movable mem-

bers, a pair of overlapping guide-plates on said movable members provided with oppositely-directed slots, a traveler working in said slots to move the movable members away from and toward each other, and means for moving the traveler.

7. A binder-frame comprising two relatively movable members, a pair of overlapping guide-plates on said members at each end of the frame, said plates having oppositely-directed guide-slots, travelers working in said guide-slots, a back member, and means connected to said back member for operating said travelers to move the movable members bodily away from and toward each other.

8. A binder-frame comprising a back member and two relatively movable members, overlapping triangular guide-plates on said movable members provided with oppositely-directed guide-slots, a traveler working in said guide-slots, and means for moving the traveler longitudinally of the frame to move the movable members bodily away from and toward each other.

9. A binder-frame comprising a back member and two relatively movable members, triangular guide-plates carried by said movable members with their bases overlapping, a channel on the base of one plate forming a guide for the base of the other plate, guide-slots in said plates, a traveler operatively engaging said slots, and means for moving the traveler.

10. A binder-frame comprising a back member and two relatively movable members, a set of overlapping triangular guide-plates carried by the movable members at each end of the frame, oppositely-directed slots in said guide-plates, travelers working in said slots, and a screw-rod for moving said travelers longitudinally of the frame to move the movable members bodily away from and toward each other.

WILLIAM J. WATTERS.
